ATTORNEY

UNITED STATES PATENT OFFICE

HANCIL CORDREY, OF CHULA VISTA, CALIFORNIA

CATCH

Application filed September 20, 1926. Serial No. 136,441.

My invention relates to catches for latching or locking casement windows, transoms, small doors and the like.

The objects of my invention are: first, to provide a particularly simple and economically constructed catch for positively holding windows and doors in their closed positions; second, to provide a catch of this class which is equally applicable to outwardly or inwardly swinging windows, doors and the like; third, to provide novel means for adjusting the relative positions of the main catch member and the keeper; fourth, to provide a resilient catch for windows, transoms, doors and the like which serves as a shock absorber against the initial impact of the closing window, transom, door and the like so that the same will not readily slam against the jamb or frame; fifth, to provide a catch of this class having a knob in association therewith whereby the window, door or the like may be readily gripped for opening or closing the same, which knob serves also to facilitate the distortion of the catch member against the spring action thereof, whereby the catch may be readily unlocked and the window or door opened; sixth, to provide as a whole a novelly constructed catch of this class, and seventh, to provide a catch of this class which is durable, practical and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a fragmentary sectional view taken through the free edge of a transom or similar swinging member and its jamb, showing my catch structure in connection therewith; Fig. 2 is a front elevational view thereof, also showing the transom and the jamb fragmentarily; Fig. 3 is a view of one of the keeper members, showing the adjusting cor-

rugations therein; Fig. 4 is a fragmentary sectional elevational view of a window-sill and casement window, showing a slightly modified form of construction of my catch in connection therewith, and Fig. 5 is an inside elevational view of a fragmentary portion of a casement window and frame, showing the modified form of construction of the catch, shown in Fig. 4, applied thereto.

Like characters of reference refer to similar parts and portions throughout the several views of the drawings.

The one form of construction of my catch, as shown in Figs. 1, 2 and 3 of the drawings, consists essentially of a resilient catch member 1, a keeper or striking plate 2, a keeper retaining plate 3, a knob 4 and screws 5, 6 and 7.

The catch shown in Figs. 1, 2 and 3 is applied to a transom or any other window or door opening into the room of the building, or in any other similar location. The catch member 1 in this form of construction is provided with a U-shaped portion 1^a which is positioned between the free edge of the window or door and the window jamb or door casing, preferably by mortising said portion into the edge of the window or door, as shown in Fig. 1. The one leg of this U-shaped portion 1^a is secured to the edge of the window or door by means of a screw 5 secured to the window or door through a hole 1^e in the other leg of the U-shaped portion 1^a. The leg of the portion 1^a through which the screw 5 extends is bent at a right angle at its outer end, as indicated by 1^b, which portion is secured to the front side of the window or door by means of a knob 4 and a screw 7 extending through the knob and the flange or portion 1^b into the front side of the window or door, as shown in Fig. 1. The other leg, in which the hole 1^e is provided, extends a slight distance beyond the front face of the window or door and is offset towards the knob 4, as indicated by 1^c, and thence bent outwardly 95 in curved form, as indicated by 1^d, the curvature of the portion 1^d conforming with the curvature of the knob.

Against the adjacent side of the door or window jamb is secured the keeper or strik-

ing plate 2, which is preferably mortised into the jamb, as shown in Figs. 1 and 2. This keeper or striking plate 2, shown in plan in Fig. 3, is provided at its outer end with a keeper or striking portion 2^a bent outwardly a slight distance from its main plate portion. The normally outer side of the plate portion 2^b of the member 2 is provided with transverse grooves or serrations, as shown in Figs. 1 and 3. Against this grooved portion of the keeper or plate 2 is positioned a correspondingly grooved face of the retaining plate 3, which plate 3 is secured, by means of a screw 6, to the jamb of the window or door. The hole 2^c in the member 2, through which the screw 6 extends, is elongated, as shown in Fig. 3. This elongated hole 2^c permits the keeper or striking plate 2 to be adjusted inwardly or outwardly relatively to its retaining plate 3 and the window or door, without removing the retaining plate 3, and provides at all times a rigid position for the keeping or striking portion of the member 2.

The free or longer outer leg of the catch member 1 is provided at its outer side with a lug 1^f bent outwardly from the leg of the catch member. The front edge of this lug 1^f is adapted to engage the portion 2^a of the keeper 2 when the window or door is closed. The back side of the lug 1^f is inclined at an angle and adapted to engage the edge of the portion 2^a of the member 2 for automatically depressing the free leg of the catch member 1 when the door or window is shifted to a closed position. The inclination of the back side of the lug 1^f is such, however, that if the window or door is slammed to its closed position, the inclined side of the lug will take up considerable of the shock and thus serves as a shock absorber against the slamming of the door or window.

The knob 4 permits the door or window to be readily opened and at the same time provides a grip against which the curved portion 1^d of the catch member 1 may be depressed for disengaging the lug 1^f from the retaining or keeper portion of the keeper or striking plate 2.

In Figs. 4 and 5 of the drawings, my catch structure is slightly modified to conform with the structure of an outwardly swinging window or door. In both views 4 and 5 the latch structure is identical, the latch in Fig. 4 being applied at the lower end of the window or door and the sill, while in Fig. 5 the same is applied to the side of the window or door and the jamb.

The catch member, indicated by 8, in this modified form of construction is constructed in the form of a right angle with the one flange 8^a secured to the inner side of the casement window or door in a manner similar to the other structure, namely, by means of the screws 5 and 7, the latter screw also securing the knob 4 over the outer side of said

flange and to the window or door. The other flange 8^b of the jamb member extends at a right angle to the casement window or door into the room and is provided at its free end with a loop or grip portion 8^c, the outer end of which is positioned contiguous to the knob 4 so that the free end of the portion 8^c may be readily shifted or depressed when the knob 4 is gripped. The loop portion 8^c is provided with a hole 8^d, as shown best in Fig. 5, to permit the screw 5 to be readily secured. The outer or under side of the free flange 8^b of the catch member is provided with the catch lug 8^e, which is preferably punched from the plate forming the catch member. This lug is preferably secured near the end of the flange 8^b of the catch member, as shown best in Fig. 4. The outer and back side of the lug 8^e is inclined at an angle to provide for automatic depression of the free end of the catch member when the window or door is shifted to a closed position and also to serve as a shock absorber, as described above. The keeper 2 in this modified form of construction is positioned on the outer side of the retaining plate 3. The keeper and retaining plates 2 and 3 in this form of construction are similarly provided at their adjacent sides with interlocking, transversely positioned grooves for holding the keeper plate in a certain adjusted position. The keeper plate 2 is also provided with an elongated slot to permit the same to be adjusted relatively to the plate 3 without adjusting the latter plate, said plates being secured to the sill or to the jamb of the window or door frame by the screw 6, as in the previously described structure.

In the structure shown in Figs. 1, 2 and 3, the free end of the catch member is provided with a pair of holes 1^g, preferably in the curved grip portion 1^d thereof. Through these holes may be secured a cord for depressing the grip portion when the catch is used in connection with transom windows.

Though I have shown and described a particular construction, combination and arrangement of parts and portions and a slightly modified form of construction thereof, I do not wish to be limited to this particular construction, combination and arrangement nor to the modification, but desire to include in the scope of my invention, the construction, combination and arrangement substantially as set forth in the appended claims.

Having thus described my invention, what I claim as new and desire to secure by Letters Patent is:

1. In a catch structure, a catch member formed of a resilient plate and adapted to be secured at its one end to a window or door, said plate being provided intermediate its ends and at its normally outer side with a lug with its engaging end cut and pressed out of the middle portion of said plate and at its opposite end with means to facilitate the

shifting of the free end of said catch member and the lug thereof inwardly, and a keeper adapted to be rigidly secured to the frame of said window or door and provided with an outwardly extending projection forming a ledge on the surface of said frame adapted to be engaged by said lug for depressing the same and the free end of the catch member and for holding said lug in a positive locked position.

2. In a catch structure, a catch member formed of a resilient plate and adapted to be secured at its one end to a window or door, said plate being provided intermediate its ends and at its normally outer side with a lug with its engaging end cut and pressed out of the middle portion of said plate and at its opposite end with means to facilitate the shifting of the free end of said catch member and the lug thereof inwardly, said lug being inclined at its outer side, and a keeper adapted to be rigidly secured to the frame of said window or door and adapted to be engaged by the inclined side of said lug for depressing the same and the free end of the catch member and for holding the end of said lug in a positive locked position.

3. In a catch structure, a catch member formed of a resilient plate and adapted to be secured at its one end to a window or door, said plate being provided intermediate its ends and at its normally outer side with a lug with its engaging end cut and pressed out of the middle portion of said plate and at its opposite end with a grip portion to facilitate the shifting of the free end of said catch member and the lug thereof inwardly, and a keeper adapted to be rigidly secured to the frame of said window or door and forming a ledge on the surface thereof and adapted to be engaged by said lug for depressing the same and the free end of the catch member and for positively retaining said lug in a locked position.

4. In a catch structure, a catch member formed of a resilient plate and having a U-shaped portion, the one leg of said U-shaped portion being adapted to be secured to the free edge of a swinging window or door with the connecting end of said U-shaped portion extending toward the inner side of said window or door, the other leg of said U-shaped portion extending beyond the outer side of said window or door providing means to facilitate the depression thereof, said latter leg being provided at its outer side with an inclined lug, with its engaging end cut and pressed from the middle portion of said plate inclined at its outer and forward side, and a keeper adapted to be rigidly secured to the frame of said window or door and forming a ledge on the surface thereof and adapted to be engaged by the inclined lug of said catch member for depressing the same

and for holding said lug in a locked position.

In testimony whereof, I have hereunto set my hand at San Diego, California, this 9th day of September, 1926.

HANCIL CORDREY.
